(57) **CLAIM**

The ornamental design for a pet hair clipper, as shown and described.

DESCRIPTION

FIG. 1 is a front, right and top perspective view of a pet hair clipper, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is an enlarged detail view of portion 9 encircled in FIG. 1.

The evenly-spaced broken lines shown in the drawings illustrate portions of the pet hair clipper and form no part of the claimed design.

The dot-dash broken lines illustrate the boundaries of the enlarged view indicators and form no part of the claimed design.
